ROLLIN C. LEWIS, OF STAMFORD, CONNECTICUT, ASSIGNOR TO THE YALE & TOWNE MANUFACTURING COMPANY, OF STAMFORD, CONNECTICUT.

DIAL FOR COMBINATION-LOCKS.

1,286,035.

Specification of Letters Patent. Patented Nov. 26, 1918.

Application filed October 10, 1917. Serial No. 195,784.

To all whom it may concern:

Be it known that I, ROLLIN C. LEWIS, a citizen of the United States, and a resident of Stamford, in the county of Fairfield and 5 State of Connecticut, have invented certain new and useful Improvements in Dials for Combination-Locks; and I do hereby declare the following to be a full, clear, and exact description of the invention, such as will enable others skilled in the art to which it 10 appertains to make and use the same.

My invention relates to an improvement in dials for combination locks.

The object of the invention is to combine 15 mechanical excellence with economy of construction, and it consists in the details of construction as will be more fully explained and pointed out in the claims.

In the accompanying drawings, Figure 1 20 is a view of a dial mounted in its ring; Fig. 2 is a view of the dial and its spindle removed from the ring; Fig. 3 is a view in section through the dial and its spindle; Fig. 4 is a view of the dial core and its struck up 25 cover before they are assembled, and Fig. 5 is a rear view of the dial.

In order that a dial may operate properly and concentrically within its surrounding ring, it is necessary first, that the spindle be 30 properly centered, and second, that the dial itself should be accurately made so that its periphery is a true circle, and it is also desirable for perfect operation, that the dial be sufficiently heavy so that when revolved it, 35 will have a certain amount of inertia.

Heretofore it has been the custom to make the dials of combination locks solid, either out of cast bronze or brass, which is expensive, or to make them out of stamped up 40 bronze or brass of light gage, which is objectionable, first, because the dial thus produced is too light, and second, that tools used in their construction bend and become impaired from constant use and lose their accuracy, so that the dials are not absolutely circular and will consequently bind at points, with the surrounding ring.

This invention resides primarily in combining the inexpensive core 6, with a struck 50 up dial 7. The core 6 may be made of cast iron or other cheap metal, or it may be struck up or turned on a lathe, and conforms in shape and design to the finished dial. It is provided with an outwardly projecting 55 knob 8, and its periphery is milled or notched

as at 9, so that when the covering 7 is secured thereon, the metal of the cover or struck up dial 7 will embed itself in the notches in the periphery of the core and thus absolutely lock the cover against any movement on the core. 60

The core 6 and its knob 8 are bored and threaded to receive the spindle 10, which latter is preferably threaded its entire length to provide for indefinite adjustment, and is also 65 provided with a groove 11, to receive a spline 12 which, engaging the seat 13 in the hub 14 of the core, locks the spindle against movement in the core. The hub 14 of the core is cylindrical and is preferably fitted with a 70 bronze, brass or other non-corrosive sleeve 17 so that it will rotate freely in the lock.

The struck up dial 7 is preferably of 75 brass, bronze or other suitable metal which will be ornamental in appearance and present a finish that will be lasting. The blank for the struck up dial 7 is shaped to fit over the knob and core, and then by spinning the edge of the blank around the periphery of the core, and by rolling the base of the 80 knob portion of the blank, into a corresponding depression 16 in the core, the struck up dial or covering 7 becomes permanently locked to the core. Instead of making the dial 7 of struck up metal, it may be made 85 of a composition such as rubber or other non-corrodible substance.

If desired the outer end of the knob may be counterbored and the cover provided centrally with a hole as shown to receive 90 the female threaded boss on the rear face of a disk 15, which latter may have a trade name or other mark on its outer or exposed face. This disk overlaps the cover plate and holds it in place and against the outer 95 face of the knob, and also gives an ornamental finish to the dial.

Having fully described my invention what I claim as new and desire to secure by Letters-Patent, is:—

1. As a new article of manufacture, a dial for a combination lock consisting of a metal core having a milled periphery and provided on its front face with a centrally located knob having a restricted neck, and a 105 cover of superior material forced against said restricted neck and shaped to conform to the outer face and knob of the core, the outer edge of the cover being forced into the milled periphery of the core. 110

2. As a new article of manufacture, a dial for a combination lock consisting of a metal core having the shape of the finished dial and provided on its front face with a centrally located knob having a restricted neck and a rearwardly projecting hub, a spindle secured to the core, and a cover shaped to receive the core and secured to the outer face of the latter by forcing it against the restricted neck of the knob, and a non-corrosive sleeve secured on the hub of the core.

3. The combination of a heavy metal core having a centrally located integral knob, a threaded hole extending through the core and knob and a recess in the knob at the outer end of the hole, a cover shaped to conform to the front face of the core and knob and having a central opening conforming to the recess in the knob, and a disk screwed 20 to the front end of the spindle and clamp-

ing the cover against the outer face of the knob.

4. As a new article of manufacture, a dial for a combination lock consisting of a solid metal core having a centrally located knob 25 and otherwise conforming in shape to the finished dial, a cover of superior metal shaped to fit the outer face of the core and the knob and provided with dial notches adjacent its periphery and with a centrally 30 located hole, and a disk secured within said hole and clamping the cover to the outer end of the knob.

In testimony whereof, I have signed this specification in the presence of two subscr- 35 ing witnesses.

ROLLIN C. LEWIS.
